PROJECTION SCREEN

Application filed February 18, 1928. Serial No. 255,280.

This invention relates to motion picture projection, and especially to a new and improved composite screen which is characterized by a high visibility at extreme angles, 5 and an exceptionally low cost.

Heretofore, considerable difficulty has been experienced in securing motion picture screens which were susceptible of use under varying conditions obtaining in moving picture theatres. This difficulty has been due to the fact that optimum reflectivity from the screens hitherto available is confined to a relatively narrow area on either side of a line representing the axis of projection of 10 the rays of light from the projector. This area is, for the average good screen, comprised within an area whose outer limits are bounded by lines varying some 30° from the axis of projection. Various expedients have been 15 tried to secure an extension of the angle of visibility, but such results are secured at the expense of the depth of reflection of the projected picture.

A further disadvantage of the screens hitherto used, resides in their high initial cost and their gradual deterioration due to the deposition of atmospheric dust and dirt in 25 the fibres of the screen.

It is an object of the present invention to 30 provide a screen which is at one and the same time characterized by high reflecting power and a wide range of diffusion characteristics.

It is a further object of the present invention to provide a screen of the type designated 35 which is relatively cheap in cost and readily replaceable, whereby optimum projecting conditions may be maintained without undue expense.

Yet another object of the present invention is the provision of such a readily replaceable screen, which may optionally be comprised of a plurality of separate units.

Still another object of the invention is the provision of an improved projection screen 45 apparatus which is designed to afford maximum service coupled with ease of replacement of the screen member proper.

A further object of this invention is the provision of a plurality of improved screen 50 members, so constituted and arranged as

to occupy a minimum of space and thus afford considerable savings in transportation charges.

These and other important objects and advantages of this invention will be described 55 in this specification and illustrated in the accompanying drawings, it being understood that they are given by way of illustration only, as the underlying features may be incorporated in a variety of devices without departing from the spirit and scope of the invention. 60

In the drawings, like numerals refer to 65 similar parts throughout the several views of which

Figs. 1, 2 and 3 are enlarged cross-sections of screens suitable for use in the present invention;

Fig. 4 is a front view of a frame for supporting the composite screen; 70

Fig. 5 is a cross-section of the frame showing the clamping or retaining means for the screen;

Fig. 12 is a schematic showing of a method of joining a plurality of screen members to form a large screen;

Fig. 13 is a schematic showing of the reflection characteristics of a screen of the present invention in comparison with screens of the prior art; and

Fig. 14 is a graphical representation of the curves illustrated in Fig. 13. 95

As intimated hereinbefore, projection screens vary in their optical properties to such an extent, that in any given installation, the particular type of reflecting surface used must be carefully figured out beforehand in 100

order to secure optimum visibility on the part of spectators seated in various parts of the auditorium and at diverse angles from the axis of projection.

5 The screens of the prior art show a remarkable variation in reflection characteristics, ranging from surfaces which almost completely diffuse the incident light to screens of a very specular nature, having very high reflecting powers on the projection axis and very low values in directions departing by relatively small amounts from the normal. It is, therefore, quite obvious that no one type of screen with fixed characteristics, can be 10 adapted for use in rooms of varying shapes.

As an example of the difficulties to be met, it will readily be observed that if the length of a room be large relative to its width, the use of a screen of the completely diffusing type is 15 very wasteful of light, and the necessary screen brightness can be obtained over the required angle by the use of a screen which reflects a large proportion of the incident light within a relatively narrow angle, thus effecting considerable economy in operation. Where such a specular reflecting type of screen is employed in a room whose length is relatively small compared with its width, a light source of high power would not assure 20 sufficient visibility for those seated at a considerable angle from the axis of projection. While those seated more nearly in the center of the house or room are subjected to an uncomfortable brightness or high glare due to 25 the almost direct reflection of the intense light rays.

These difficulties are overcome by the present invention in which an efficient reflecting surface of such suitable diffusing characteristics, is provided by a surface of manganese carbonate or like substance. This material has a diffuse reflecting characteristic which combines the good properties of specular, metallic reflecting surfaces, and the diffusing, 30 pigment surfaced screens. Referring to Figs. 13 and 14, there is shown graphically the optical characteristics of a screen A of the present invention compared, for purposes of illustration, with a screen of each of the specular B and diffuse C types.

As shown in the figures referred to, the visibility of screen A is very high at an angle of 70° from the axis of projection, the drop in visibility or reflecting power, (on a basis of 35 magnesium oxide having an arbitrary reflecting power of 100), is from approximately 98 at 0° angle to approximately 70 at 70° angle. Screen B, which is of the reflecting type, is characterized by an extremely high 40 reflecting power within an angle of 20° from the axis of projection, which rapidly decreases with slight increases in the angular variation to a low value of 35 at 40° angle and by successive decrements to 20 at 70° angles. 45 Such a type of screen is, therefore, of neces-

sity restricted in its field of use to rooms in which the effective lateral angle of visibility does not vary more than about 30° from the axis of projection. Screen C, which is an exemplar of the diffuse type of projection surfaces is characterized by an initial reflecting power of about 150, which drops sharply to a value of about 60 at 20° from the axis of projection, and at 70° has a nominal value of 25, which is approximately that of screen B at such an angle. It is to be noted that screen A has a higher reflecting power for all angles greater than 30° from the axis of projection than the typical screens considered.

The optimum areas of visibility for the three types of screens are diagrammatically shown in Fig. 13, in which the axis of projection is designated generally by the line X—Y, the screen being placed at X and the motion picture projector at Y. It will be seen from this showing that screen A is characterized by an extreme power of diffusibility of incident light, together with a reflecting power which approximates that of the true specular or reflecting type of screen.

The foregoing optical considerations have been predicated upon the use, for example, of finely divided magnesium carbonate, ground to a fineness of 200 mesh or more, and associated with or incorporated in a fibrous material in a manner now to be described.

In Fig. 1, there is shown a section of a screen, comprising a fibrous body 1, of paper, or the like, which may or may not be backed up with a reinforcing cloth or other support, as desired. A layer of suitable adhesive material 2, is applied to one surface of sheet 1, and over this is sprinkled a layer of finely divided magnesium carbonate 3. The carbonate layer may be applied to the adhesive in any other manner, as by placing an excess of the material on the adhesive, removing the excess, and applying pressure to the surface to smoothen it out.

In place of applying magnesium carbonate to the adhesive layer, as described, it may be incorporated in the body of the paper by adding it to the pulp in the beating engine, and then subjecting the resultant pulp to the usual steps in the papermaking process. Such a magnesium carbonate impregnated paper is shown in section in Fig. 2 and is designated generally by the numeral 4. In addition to incorporating a light reflecting and diffusing component, such as magnesium carbonate, in the paper sheet, pigments may be added for a purpose which will now be described.

As is well known, certain portions of the spectrum of the projected beam are undesirable, and it is customary to filter out such undesirable components by interposing tinted screens between the source of light and the projection screen. Such filters create a loss

of effective projecting power at the projector. By the use of appropriate pigments in the paper, in conjunction with the carbonate or other reflecting material, certain undesirable portions of the spectrum of the projected beam are absorbed and the remainder is reflected back to the audience as a rectified light, which results in creating a more desirable appearing screen. By this means there is secured a more efficient utilization of the initial projected light, which enables the production of results much superior to the ones now obtained.

Where it is not desired to expend the money necessary to produce an impregnated sheet of the type described, the procedure described in relation to the showing in Fig. 1 may be modified as designated in Fig. 3. Here the base sheet of heavy paper of any appropriate strength desired, is coated with an adhesive in which has been incorporated a sufficient quantity of the magnesium carbonate, or its equivalent. Any desired pigment may be associated with the carbonate adhesive composition, for the purposes above designated.

By the use of the paper screens of the present invention, the initial cost of installing a reflecting surface is very considerably cheapened, and in addition, the replacement cost is so low that relatively frequent renewals of the screen surface are possible without being inhibited by the uneconomical high costs of the screens now in use.

In adapting the improved screens of the present invention to standard installations, it is sometimes necessary to combine two or more paper screens in order to secure the requisite size. This is due to the fact that the width of paper normally available for the purposes described is not sufficient for large screens, the present constructions being composed of a plurality of interwoven sheets of fabric prepared without seams.

Referring now to Figs. 4 and 5, there is shown a suitable frame comprising top and bottom pieces 6 and 7, and side pieces 8 and 9, together with an intermediate cross piece 10. These members are joined together to form a firm, integral structure by any suitable means well known to those skilled in the art. The several members are provided with inwardly curved surfaces 11, which, in effect, assures a single line support around the periphery of the frame and across the cross-piece. The function of this single line support feature will be discussed more in detail hereinafter.

The screen sections 12 and 13, Fig. 5, are brought around the members 6 and 7 respectively, the ends 14 and 15 being held tight by means of clamps 16 acting through supports 17. The previously beveled ends 18, 18' of sections 12 and 13 are coated on their adjacent portions with a suitable adhesive and held in

position during setting by a special clamp comprising a frame member 19 and removable end clamps 20, 21 adapted to fit over the ends of the member 19 and hold it in cooperating relation to side pieces 8 and 9. Wing screws 22, 23, are tapped into angle portions 24, 25 of the clamps and serve to hold the latter in position, as above noted. When the adhesive has set, the clamp structure is removed and the joint 18, 18' smoothed by a roller or any other suitable means, if necessary.

By the process set forth, a projection screen of any desired size can be made up in situ, with a minimum of labor and expense, and susceptible of easy replacement at low cost.

While the edge portions 18, 18' have been spoken of as being both beveled, it is obvious that one edge only, e. g., 18, need be beveled or skived to secure the desired result. It is also to be noted, that while the screen sections have been joined with the top section overlapping the bottom, the condition may be reversed, or the sections may be secured together with a longitudinal joint instead of a horizontal one, the frame and its associated parts lending themselves readily to such transposition. The position of the seam in the completed screen will be determined by the relation of the projector thereto.

The sheets of magnesium carbonate coated or impregnated paper may be wound on rolls, positioned respectively at the top and bottom of the frame, or they may be placed to one side of the screen in a light proof box, which construction being a preferred one for large installations, will be described in detail later on.

In Figs. 7 and 8 is shown an optional construction of the frame members, where the completed frame is too large to be conveniently shipped, and a knockdown or collapsible construction is desired. As shown, the improved frame comprises a plurality of frame units 30, 31, composed of quarter-round frame members 32, joined as already described under Fig. 4. At the abutting faces 33, 34 of the units there is provided a plurality of pins 35 joined to the top of the lower frame unit in any suitable manner, and in register with a plurality of sockets 36 in the lower frame member of the upper unit. This construction assures the proper register of the several units, which may then be clamped, or otherwise held to form a rigid frame.

In the frame structures shown, it will be noted that the paper of the screen contacts therewith at the edges of the quarter-round members around the periphery of the frame and across the center-piece. Such a condition prevents the screen from laying on a flat piece of wood or metal and bellying at the inner edge thereof. This condition is readily observed in any frame in which fabric is supported on substantially flat supporting members, and the construction devised for use in

the present invention has as its primary function the securing of an optically flat projecting surface which is absolutely essential for good motion picture projection.

5 As hereinbefore intimated, an especially desirable feature of the present invention is the provision of a large screen surface which may be readily replaced at a low cost and with a minimum of time and labor. Referring now 10 to Figs. 9 and 10, there is shown a stage drop or support comprising top, side and bottom members 40, 41 and 42 respectively. These members are recessed, as at 43 to receive a frame 44, constructed as above described. 15 This frame is held in position in the recesses of the support by any suitable means, as by screws 45, 46. At one side of the support, or at the top or bottom as desired, is a light-proof magazine comprising front and back 20 walls 47, 48, and an end door 49 attached to the back wall by hinges 50. A suitable latch, not shown, may be provided to hold the door closed.

25 Inside the light-proof cabinet are positioned the roll supports 51, 52, 53 and 54. The supports are secured to the cabinet in any desired manner. Supports 53, 54 are provided with removable and adjustable clamping jaws 55, held in coacting relationship to the 30 shafts 57 of the rolls 58, 59 by wing bolts 56.

35 The fabric on the rolls overlaps for an appreciable amount as shown at 60, to permit the formation of a screen joint, previously described. When it is desired to prepare a new screen or replace an old one, the fabric on the rolls is drawn across the frame from out of the light-proof box and the joint is prepared in the manner previously described, the far edge of the composite sheet being 40 clamped to the frame. The sheets of fabric, instead of overlapping, may merely abut or be adjacent to each other, and the desired joint between them readily secured by superposing a relatively narrow strip of the fabric 45 over the edges, and then clamping the whole assembly in the usual manner. Both edges of the intermediate strip are beveled, which feature involves further savings in installation and replacement costs. The necessary 50 tension on the roll end of the fabric is secured by the coaction of the braking clamps 55, and the tension roll 61 journalled in sockets 62, at either end of the light-proof chamber. If desired, the rolls may be provided with a 55 winding mechanism, not shown, for the purpose of securing the necessary tension of the screen after assembly.

60 The aperture 63 in the support member abutting and forming part of the light-proof chamber, serves to keep dust out of the chamber as well as to prevent the penetration of the light rays from the projector.

65 Where an exceptionally large screen surface is desired, or where, from reasons of economy, narrower fabric is to be used, any

number of rolls may be positioned within the light-proof chamber without departing from the spirit and scope of the invention.

The light chamber, among other features, preserves the reserve screen surfaces in perfect condition for an indefinite period. 70

A further novel feature of the present invention is the provision of a plurality of reflecting sheets of fabric made as above described and comprised within a pack as 75 shown in Fig. 11. This feature is characterized by a series of reflecting surfaces 70, separated by sheets of opaque material 71. These surfaces are designed for use in small or temporary installations, where a 80 standard size screen is not needed or the space available does not permit its use.

85 These packs of alternately disposed screen surfaces and opaque sheets can be made up at a central plant and shipped to outlying districts at a minimum of cost both for manufacture and expressage as well as for installation. When they are received, it is merely necessary to support the pack in a suitably positioned frame, tear off the protecting opaque 90 sheet, and the first screen is ready for use. When the first screen surface has deteriorated through use or age, it and its underlying protecting sheet are torn off and a 95 fresh surface is immediately available. The opaque protecting sheets are used to prevent deterioration of the underlying screen surfaces, as the projecting arcs and lamps now in use are sufficiently powerful to project 100 light of such intensity, that ordinary fabric, either paper or cloth, even when heavily loaded or sized, is readily penetrated.

105 In Fig. 12 there is diagrammatically shown a method of joining several sheets to form a screen. The members 70a and 70b are joined along their lateral edges, the edge of sheet 70b being shown folded back to show the relative position of the sheets, as are members 70c and 70d, and the resulting composite 110 sheets are joined together along the line M—N to form a screen of the desired size. This form of association of small sheets of the type suitable for use in a pack, renders 115 available the new and improved motion picture screen of the present invention in any locality, and is especially adapted for emergency or large temporary installations.

120 While it has been stated herein that paper or another commodity may be used as the base or support for the manganese carbonate or other preferred coating, it will be understood that this base or support may be of non-inflammable material. When desired and 125 with the use of paper the non-flammable condition of such paper may be obtained by treating the same with zinc chloride or other desirable fire proofing agents. When material other than paper may be used for the base or support it may be treated by any 130

suitable material to obtain the non-flammable condition.

While the improvements comprehended within the spirit and scope of the present invention have been discussed in relation to their use in motion picture projection, it is to be understood that the underlying features may be incorporated in other optical instruments, such as photometers and light 10 measuring instruments generally.

It will now be appreciated that there has been provided a new and improved motion picture screen which is suited for use in any type of room, or location, so as to be universally available for such purposes. It will also be appreciated that the screen pack disclosed is a notable advance in the art, and renders the improvements of the present invention generally available, and particularly 20 for small or temporary installations, such as may be used in "home-movies". There has also been provided a mechanism adapted to make the screens of the present invention readily replaceable at a low cost and a minimum expenditure of labor.

What is claimed is:

1. A projection screen comprising a plurality of strips of carbonate coated paper joined at their adjacent edges by integral 30 skived portions thereof in overlapping relation to form a substantially invisible seam.

2. A projection screen comprising a plurality of strips of fabric having a reflecting surface characterized by a high light-diffusing capacity, said strips being joined at their adjacent edges by integral, bevelled portions thereof in overlapping relation, to form substantially invisible seams.

3. A projection screen housing, including 40 in combination, a frame, a guide member on the frame, and a plurality of screen rolls journaled on the frame adjacent the guide member.

4. A projection screen assembly, including 45 in combination, a frame, a guide roller on the frame, a pair of screen rolls journaled on the frame adjacent the guide roller and in staggered relation to each other, fibrous screen material on the rolls and adapted to be withdrawn therefrom across the frame in overlapping relation to form a continuous screen surface.

5. A projection screen assembly, including 55 in combination, a frame, a guide roller on the frame, a plurality of screen rolls journaled on the frame adjacent the guide roller and in staggered relation to each other, fibrous screen material on the rolls and adapted to be withdrawn therefrom across the 60 frame in overlapping relation to form a continuous screen surface.

6. As an article of manufacture, a composite projection screen, including in combination, a plurality of opaque flexible strips 65 having reflecting surfaces having the optical

characteristics of magnesium carbonate, said strips being separate and positioned in overlapping relation to each other whereby to provide a continuous screen surface.

7. As an article of manufacture, a composite projection screen, including, in combination, a plurality of opaque flexible strips having reflecting surfaces having the optical characteristics of magnesium carbonate, said strips being separate and positioned in overlapping relation whereby to provide a continuous screen surface, a frame for said composite screens, said frame including top, bottom, side, and back members and a laterally positioned roll chamber, a guide member between the chamber and the frame, and means in the chamber for operatively mounting a plurality of rolls of the aforesaid flexible screen strips.
